PIPE AND TUBE BENDER

Thomas W. Delaney, St. Paul, Minn.

Application November 19, 1940, Serial No. 366,298

14 Claims. (Cl. 153—39)

This invention relates to a pipe bending machine.

An object of the invention is a provision of the machine for bending pipes through various arcs in which the bending element is followed by a pipe supporting element in a curved path which defines the curve of the completed bend of the pipe.

Another object of the invention is a provision of the machine for bending pipes through various arcs in which one end of the pipe is secured in position on a table, the remaining portion of the pipe projecting freely beyond the secured end of the pipe, a frame pivotally mounted in straddling relation with the projecting end of the pipe and carrying a movable bending jaw or block which when operated exerting pressure on the pipe to cause bending of same, a supporting block spaced from the bending block and movable along an arc of a circle with the bending block for supporting the pipe at various stages during the bending operation, the length of the arc through which the pipe is bent being predetermined.

A further object of the invention is the provision of a pipe bending machine so constructed that a pipe may be bent along shorter or longer lengths with the arcs of curvature having different radii, a pipe being bent in stages and supported at each stage at points where the preceding bend has been made.

This invention will be best understood from a consideration of the following detailed description, in view of the accompanying drawings forming a part of the specification, nevertheless, it is to be understood that the invention is not confined to the disclosure, being susceptible of such changes and modifications as define no material departure from the salient features of the invention in the appended claims.

In the drawings:

Figure 1 is a side view of my bending machine in operative position.

Figure 2 is a front end view of the same.

Figure 3 is a vertical section of the bending machine.

Figure 4 is a fragmentary plan view.

Figure 5 is a horizontal section taken along the line 5—5 of Figure 1.

Figure 6 is a section taken along the line 6—6 of Figure 1.

Figure 7 is a view in perspective of a pipe supporting block in detached relation.

Figure 8 is a view in perspective of a pair of blocks for clamping the pipe rigidly in position.

Figure 9 is a fragmentary view in perspective with parts broken away showing the trunnions for supporting the bending block.

Referring more particularly to the drawings, 5 10 designates a pair of standards formed of angle iron construction which supports one end of the table 11. A second pair of standards 12 support the opposite end of the table. Each pair of standards is connected together by means of a base member 13 which is secured to the floor of a building.

Spaced legs 14 are secured at their upper ends to the front end of table 11 and depend therefrom. These legs are provided with perforations 15 which align with perforations in the standards 10 and bolts 15 and 16 are passed through the aligned perforations and secured in place by means of the usual nuts. A pair of legs 17 depend from the opposite end of table 11 and these legs are removably connected to the spaced standards 12 by means of bolts 18 and 19. The legs 14 and 17 are of angle iron construction.

A clamping device generally designated by the numeral 20 and shown more particularly in Fig.

25 8 is removably mounted on the table 11. This clamping device consists of a lower block 21 having a semi-circular groove 22 to receive the pipe and an upper block 23 having a complementary semi-circular groove 24 also to receive the pipe. The pair of bolts 25 have their lower ends as shown at 26 pivotally connected to the table 11 and are adapted to be received in grooves 27 and 28 respectively formed in the sides of the blocks 21 and 23. Nuts 28 and 29 of any suitable type are screwed on to the upper ends of the bolts for forcing the clamping block 23 tight against one end of a pipe 30. The opposite end of the pipe projects forwardly of the table 11.

A tympan frame generally designated by the 40 numeral 31 consists of a pair of legs 32 which are connected together at their lower ends by a bar 33 and at their upper ends by a bar 34. It will be noted from Figs. 1 and 3 that the legs 32 are provided with a plurality of spaced perforations

45 35 which are located in the upper portions of the legs and a plurality of spaced perforations 36 which are formed in the lower half of the legs. The perforations 35 in the upper portions of the legs are adapted to receive a pivot pin or bolt 37.

50 This bolt is of sufficient length to pass through perforations 38 formed in the spaced legs 14 for swingably supporting said frame.

A forming block 40 shown more particularly in Figs. 3 and 7 is secured by means of bolts 41 to the top bar 34 of the frame 31. It is noted that

this block is provided with a semi-circular groove 42 which receives a projecting end 43 of the pipe 30. It is to be noted from Fig. 1 that the bottom of the groove 42 is curved longitudinally in order to take care of the curvature of the bend in the projecting end 43 of the pipe at its under-face.

The pair of spring fingers 44 are secured to the upper face of the block 40 at each side of the groove 42 by the bolts 41. These spring fingers project beyond the outer face of the block 40 and are provided with bent portions 45 forming lugs for a purpose which will be presently explained. The opposite ends of the fingers are also bent upwardly as shown at 46 and 47 and a latch member 48 is curved along the arc of the circle which corresponds to the curvature of the pipe which is being bent. One end of the latch member is perforated as is the bent-up portion or ear 47 to receive a pivot pin 49. Thus it will be seen that the latch member may be swung upwardly and away from the groove 42 when a pipe is being inserted or being removed from the block 40. The other end of the latch member is perforated as is the ear 46 to receive a pin or other fastening means 50 for retaining the free end of the latch member in place.

A spring 51 secured at 52 to the under-face of the table 11, projects forwardly of the table and downwardly and is in engagement with the bar 34 on the frame 31. In other words, this spring supports the upper end of the frame 31 at a time when the first bend is being formed in the projecting end 43 of the pipe.

A coil spring 53 has one end secured to a bar 54 mounted transversely of the table 11 and rigidly carried by spaced hangers 55 depending from the table 11. The other end of the spring as shown at 56 is secured to a pin on one of the legs 32 of the frame 31. This spring tends to pull the frame 31 towards the left in Figs. 1 and 3 and thus will tend to maintain the frame in its upright position.

A second frame generally designated by the numeral 60 consists of a pair of spaced legs 61 which are connected together at their lower ends by a bar 62. These legs are provided with a plurality of perforations 63 in the upper part adapted to receive the bolt 37. A plurality of perforations 64 is formed at the lower portions of the legs 61 which may also receive the bolt 37 for swingably supporting the frame.

A spring 65 has one end secured to the bar 66 which is rigidly supported by spaced hangers 67 depending from the table 11. The other end of the spring is connected to a pin 68 carried by one of the legs 61 of the frame 60. Since the spring is in tension it will tend to maintain the frame 61 in an approximately vertical position.

The upper end of each leg 61 of the frame 60 is provided with a passage 70 which receives the ends of a pin 71 upon which is mounted a sleeve 69 having eccentrics 72, 73 and 74. Said pin has a working fit within the eccentric sleeve and in the passage 70 in the legs 61 and is readily removable therefrom when the pipe 30 is inserted or removed from the clamping elements 21 and 23.

A pair of disks 75 are located in spaced relation and each disk is provided with a passage 76 which is eccentric to the pin 71 to receive the eccentric portion 74 of the sleeve 69. This sleeve is provided with a pair of spaced collars 77. One face of each collar abuts the inner face of the adjacent disk 75 with the collars being housed by a split ring 78 which is secured at 79 to the

adjacent disk for rigidly securing the disks to the sleeve.

Each disk is provided with a projection 80 which extends downwardly and in close association with a respective leg 61 of the frame 60. Each projection is provided with journals 80a at the lower ends thereof.

A bending block 81 is pivotally mounted at the inner free ends of the projections 80 by means of semi-circular trunnions 82 which are received within the journals 80a in the lower free ends of the extensions. It will be noted from Figs. 1 and 3 that the outer face of the bending block 81 is in engagement with the lugs 45 on the spring fingers 44. The block 81 is provided with a longitudinal groove 83 to receive the projecting end 43 of the pipe which is being bent. The lower edges of the bending block are in flat contact with the spring fingers 44.

An operating lever generally designated by the numeral 85 consists of a pair of spaced bars 86. The inner ends of the bars 86 are provided with openings to receive the eccentric portion 73 of the sleeve 69.

The spaced bars 86 of the lever 85 are provided with slots 87 to receive an elongated key 88, which is adapted to be received by notches 89 or 90 in each of the disks 75. When the power lever 85 is operated by hand, the key 88 is located in the notches 89 of the disks. While, when the lever is operated by a motor 91 the key is placed in the notches 90 of the disks 75, as will be presently explained.

In order to maintain the key 88 in engagement with the notches, a yoke 92 is forced against a reduced central portion 93 of the key by a crank shaft 94 operated by a crank 95.

When the power lever 85 is operated by the motor 91, a bolt or pin 96 is inserted through passages 97 in the bars 86, and also through bearings 98 on the upper ends of the rods 99. After the key 88 has been released from the position shown in Fig. 1 in full lines and the lever 85 has been moved to the dotted line position, and after the lever has reached the dotted line position the key 88 is then forced into position by the operation of the crank 95 and retained in the slot 89.

The rods 99 are connected to eccentric pins 100 on wheels 100a which are driven by a shaft 101, and this shaft is driven by a worm wheel 101a. A worm 102 which is connected to a motor shaft 103 of the motor 91 drives the worm wheel 101a. The motor 91 is connected by a bracket 91a to the frame 60.

The swinging movement of the frames 31 and 60 in this device determines the angle of the bend of the pipe 30. The device consists of a radial arm 105 which has a notched portion 106 receiving the pivot pin 37. Extending downwardly from the outer end of the arm 105 is a curved member 107 having a bushing 108 at its free end which receives pins 109. These pins project into one of the passages 36 in the bars 32 of the swingable frame 31 and these bars are maintained in position by a U-shaped spring 110 as shown more particularly in Fig. 6. The ends 111 of the U-shaped spring are received within passages 112 of the pins 109 and through openings 113 in the bushing 108. Thus it will be seen that when the legs of the spring 110 are forced towards each other the outer ends of the pins 109 will be moved away from the openings 36 in the bars 32 whereby the lower end of the

member 107 will be released from the lower end of the frame 31.

The outer face of the curved member 107 is provided with graduations in the form of degrees. A slideable stop 114 of sufficient length to span the vertical members 14 has a slot to receive the curved member 107. A set screw 115 is threaded into the member 114 and the inner end engages the curved arm or bar 107 securing the member 114 in position at some particular degree. The purpose of the member 114 is to determine in advance the angle of the bend in the pipe so that if the member 114 were set at 90 degrees on the curved arm 107 and the pipe end 43 is gradually bent as the frame 60 is moved through 90 degrees, the stop 114 would come to rest against the legs 14 and, therefore, further bending of the pipe would be prevented. If it is desired to bend the pipe at some other angle, the stop 114 is shifted along the curved arm 107 until the desired degree is reached as indicated on the arm. The stop is then fastened in position. The swinging movement of the frame 60 would be limited in movement to the number of degrees indicated on the curved arm 107.

The operation of my device is as follows: A pair of clamping blocks 21 and 23 are selected which will perfectly fit the pipe which is to be bent. At the same time, suitable blocks 40 and 81 are selected. When the block 40 is being secured to the upper end of the frame 31 said frame is maintained in position shown in Figs. 1 and 3 by the spring 53 while the upper end of the frame is supported by the spring member 51. After the blocks have been properly positioned pipe 39 is placed between the clamping blocks 21 and 23 whence the nuts 29 are screwed into place for clamping the pipe rigidly between the said blocks.

When the device is operated by hand the power lever 85 is in position shown in Fig. 1 in full lines. However, the lever must be raised in order to raise the block 81 sufficiently above the end of the pipe to be bent. The key 88 at this time is in the position shown in full line Fig. 3. The power lever is then pulled downwardly whence the bending block 81 will be forced against the pipe while the lower portion of the pipe is supported by the block 40.

After the first increment of the bend has been made, the lever 85 is again raised and pulled outwardly to the right in Fig. 1 so that the block 81 will be in a position to engage a section of the pipe which is outwardly of the initial position. When the frame 60 is moved upon its pivot 37 and outwardly, the frame 31 is likewise moved in the same direction because the block 81 is in engagement with the lugs 45 on the springs 44. After the frames have been positioned the lever 85 is then pulled downwardly to create a further bend.

The operations just described are repeated a number of times until the stop 114 engages the legs 14 of the table. The clamping elements are released and the pipe will then be removed.

Where it is desired to create a bend in the pipe along an arc of a different radius, the frames 31 and 60 are rotated so that the forming block 40 and bending block 81 are adjacent the clamping blocks 21 and 23. The pin 37 is then removed and inserted through perforations 38, 36 and 64 of the frames 14, 31 and 60 respectively which are spaced the desired radius from the longitudinal axis of the pipe.

When desired or when necessary the table 11

may be tilted from its horizontal position to any angle between 0 degrees and 180 degrees. In order to tilt the table, the bolts 15 are removed and one of the bolts 16 is removed. The table is then tilted until the desired angle of the table has been obtained. The bolts 15 are then replaced after perforations in the legs 14 have become aligned with certain perforations in the standards 10. During the tilting of the table beyond a predetermined degree it will be necessary to remove the stop device including the arms 105 and 107. The stop then may be replaced after the legs 14 of the table have sufficiently cleared the upper end of one of the standards 10.

When the power lever 85 is operated manually the pin 96 (Fig. 5) will be removed and the reciprocating rods 99 will have been moved to one side. When, however, the device is operated by the motor 91 the power lever 85 is then moved to the full line position shown in Fig. 3 with the key 88 locking the lever in operative relation with the disks 75. The pin or bolt 96 is then passed through the perforations 97 in the bars 86 of the lever 85 and also through the bearings 98 of the rods 99.

When the motor 91 is operating, the reciprocating rods 99 operate the lever 85. After the initial bending has been made by the inward movement of the rods 99 and the lever 85 through the operation of the motor 91, the frames 31 and 60 are rocked away from the table 11 upon the return stroke of the rods and lever. This angular advance of the frames 31 and 60 is repeated at each return stroke of the rods and at a time when the bending block 81 is released from the pipe. When the stop 114 engages the legs 14 of the table, the bend will have been completed and the motor is stopped and the pipe is then removed.

The yoke or latch 43 is always closed after the pipe has been positioned and before the bending operation is started.

When the projecting pipe as it is bent strikes the floor of the building in which the bending machine is located and interferes with further bending, all the bolts 15 and 16 are removed (Fig. 2) and the table is then tilted at an angle to the horizontal with one of the bolts 16 acting as a pivot. The bolts are then replaced in the perforations in the legs 14 where the perforations align with certain other perforations in the standards 10.

Since the table may be moved through an angle of 180 degrees, it is possible to produce a number of bends in different planes in the same pipe.

Referring more particularly to Fig. 9 it will be seen that the block 81 may be readily removed from the lower ends of the arms 80 since the trunnions 82 are substantially semi-circular as are the bearings 80a in the lower ends of said arms. When it is desired to remove the bending block 81 the same is turned to an angle of 90 degrees from the position shown in Fig. 9 whence the flat side 82a of the trunnions 82 will be vertically disposed and since the width of the trunnions between the flat side and the opposite curved side of the trunnions is less than the width of the opening 83a at the bottom of each end of the arms 80 the trunnions will pass readily through the opening. When the block is inserted in position said block is again located in the same position that it was in when it was removed so that the flat sides 82a of the trunnions

will permit the insertion of the trunnions through the opening 83a.

I claim:

1. A pipe bender comprising a table, clamping means on the table for securing one end of a pipe in position, a frame pivoted on the table, a sleeve rotatably mounted at one end of the frame, a pair of lever arms secured to the opposite end of the sleeve, a bending block pivoted at the free ends of the lever arms, an operating lever mounted on the sleeve between the lever arms, means for removably connecting the lever with the lever arms so that when force is applied to the operating lever it will exert a greatly increased pressure on the pipe for the purpose of bending said pipe, a movable forming block adapted to support the pipe inwardly of the bending block when the pipe is being bent, means supporting the forming block and arranged for movement in a path corresponding to the path of the bending block, and means for maintaining the forming block in operative relation with the bending block during bending of the work.

2. A pipe bender comprising spaced standards, a horizontally disposed table, a plurality of means connecting the table to the standards, said means being removable and adapted to be placed in various connecting positions between the table and standards for supporting the table in different angular positions relative to the standards, clamping means on the table for securing one end of a pipe to the table, a frame pivoted on the table, a bending block in the frame, means on the frame for forcing the block against the pipe to cause bending of said pipe, a movable forming block adapted to support the pipe inwardly of the bending block when the pipe is being bent, means supporting the forming block and arranged for movement in a path corresponding to the path of the bending block, said frame being swingable on its pivot so that the pipe may be progressively bent along the desired arc, and means removably connecting the bending block with the forming block for simultaneous movement along the bending arc of the pipe.

3. A pipe bender comprising a table, clamping means on the table for securing one end of a pipe in position, a frame pivoted on the table, a bending block in the frame, means on the frame for forcing the block against the pipe to cause bending of said pipe, a movable forming block adapted to support the pipe inwardly of the bending block when the pipe is being bent, said frame being swingable on its pivot so that the pipe may be progressively bent along the desired arc, means for predetermining the limits of the swinging movement of the frame in accordance with the angular bend to be made in the pipe, means supporting the forming block and arranged for movement in a path corresponding to the path of the bending block and means removably connecting the bending block with the forming block for simultaneous movement along the bending arc of the pipe.

4. A pipe bending machine comprising a table, clamping means on the table for securing one end of a pipe in position, a frame pivoted on the table and straddling the pipe to be bent, a bending block in the frame, means swingably mounting the block in the upper end of the frame, an eccentric mounting for the swingable means, a lever for operating the swingable means for causing the block to press upon the free end of the pipe, a movable forming block adapted to support the pipe adjacent the bending block, said

frame being swingable on its pivot so that the pipe may be progressively bent along a predetermined arc, means supporting the forming block and arranged for movement in a path corresponding to the path of the bending block and means connecting the blocks together for simultaneous movement along the bend arc of the pipe.

5. A pipe bending machine comprising a table, clamping means on the table for securing one end of a pipe in position, a frame pivoted on the table and straddling the pipe to be bent, a bending block in the frame, means swingably mounting the block in the upper end of the frame, an eccentric mounting for the swingable means, a lever for operating the swingable means for causing the block to press upon the free end of the pipe, removable means connecting the swingable means with the lever, a movable forming block adapted to support the pipe adjacent the bending block, said frame being swingable on its pivot so that the pipe may be progressively bent along a predetermined arc, means supporting the forming block and arranged for movement in a path corresponding to the path of the bending block, means connecting the blocks together for simultaneous movement along the bending arc of the pipe.

6. A pipe bending machine comprising a table, clamping means on the table for securing one end of a pipe in position, a frame pivoted on the table and straddling the pipe to be bent, a pin mounted in the upper end of the frame and provided with eccentrics, an arm secured to each eccentric and depending therefrom, the upper ends of the arms each being provided with a notch, a lever pivotally mounted at one end of the pin, a key carried by the lever and received by the notch for removably connecting the lever to the arms, a bending block carried by the lower ends of the arms, operation of the lever causing the block to press upon the free end of the pipe, a movable forming block adapted to support the pipe adjacent the bending block, said frame being swingable on its pivot so that the pipe may be progressively bent along a predetermined arc, means supporting the forming block and arranged for movement in a path corresponding to the path of the bending block and means connecting the blocks together for simultaneous movement along the bending arc of the pipe.

7. A pipe bending machine comprising a table, clamping means on the table for securing one end of a pipe in position, a frame pivoted on the table and straddling the pipe to be bent, a bending block in the frame, means swingably mounting the block in the upper end of the frame, an eccentric mounting for the swingable means, a lever for operating the swingable means for causing the block to press upon the free end of the pipe, a movable forming block adapted to support the pipe adjacent the bending block, said frame being swingable on its pivot so that the pipe may be progressively bent along a predetermined arc, means supporting the forming block and arranged for movement in a path corresponding to the path of the bending block, means connecting the blocks together for simultaneous movement along the bending arc of the pipe, and reciprocating means connected with the lever and means for actuating the reciprocating means.

8. A pipe bending machine comprising a table, clamping means on the table for securing one end of a pipe in position, a frame pivoted on the

table and straddling the pipe to be bent, a bending block in the frame, means swingably mounting the block in the upper end of the frame, an eccentric mounting for the swingable means, a lever for operating the swingable means for causing the block to press upon the free end of the pipe, a movable forming block adapted to support the pipe adjacent the bending block, said frame being swingable on its pivot so that the pipe may be progressively bent along a predetermined arc, means supporting the forming block and arranged for movement in a path corresponding to the path of the bending block, means connecting the blocks together for simultaneous movement along the bending arc of the pipe, reciprocating means connected with the lever and means carried by the frame for actuating the reciprocating means.

9. A pipe bending machine comprising a table, clamping means on the table for securing one end of a pipe in position, a frame pivoted on the table and straddling the pipe to be bent, a pin mounted in the upper end of the frame and provided with eccentrics, an arm secured to each eccentric and depending therefrom, the upper ends of the arms each being provided with a notch, a lever pivotally mounted at one end of the pin, a key carried by the lever and received by the notch for removably connecting the lever to the arms, a bending block carried by the lower ends of the arms, operation of the lever causing the block to press upon the free end of the pipe, a movable forming block adapted to support the pipe adjacent the bending block, said frame being swingable on its pivot so that the pipe may be progressively bent along a predetermined arc, means supporting the forming block and arranged for movement in a path corresponding to the path of the bending block, means connecting the blocks together for simultaneous movement along the bending arc of the pipe, and means pivotally mounting the bending block on the arms.

10. A pipe bending machine comprising a table, clamping means on the table for securing one end of a pipe in position, a frame pivoted on the table and straddling the pipe to be bent, a bending block in the frame, means swingably mounting the block in the upper end of the frame, an eccentric mounting for the swingable means, a lever for operating the swingable means for causing the block to press upon the free end of the pipe, a movable forming block adapted to support the pipe adjacent the bending block, said frame being swingable on its pivot so that the pipe may be progressively bent along a predetermined arc, means supporting the forming block and arranged for movement in a path corresponding to the path of the bending block, spring fingers projecting from the forming block and provided with lugs at the free ends thereof, the bending block when seated on the pipe engaging the fingers and lugs so that when the frame is rocked to a new bending position the forming block will be moved simultaneously.

11. A pipe bending machine comprising a table, clamping means on the table for securing one end of a pipe in position, a frame pivoted on the table and straddling the pipe to be bent, a bending block in the frame, means swingably mounting the block in the upper end of the frame, an eccentric mounting for the swingable means, a

lever for operating the swingable means for causing the block to press upon the free end of the pipe, a movable forming block adapted to support the pipe adjacent the bending block, said frame being swingable on its pivot so that the pipe may be progressively bent along a predetermined arc, means supporting the forming block and arranged for movement in a path corresponding to the path of the bending block, means connecting the blocks together for simultaneous movement along the bending arc of the pipe, and a latch on the forming block and engageable over the pipe for connecting the block to the pipe.

12. A pipe bender comprising a table, clamping means on the table for securing one end of a pipe in position, a frame pivoted on the table, a bending block in the frame, means pivotally mounting the block on the frame, means actuating the pivoted means for forcing the block against the pipe to cause bending of said pipe, a movable forming block adapted to support the pipe inwardly of the bending block when the pipe is being bent, said frame being swingable on its pivot so that the pipe may be progressively bent along the desired arc, a swingable means having a common pivot with the frame and carrying the forming block, springs tending to retain the frame and swingable means in a substantially vertical position, and means removably connecting the bending block with the forming block for simultaneous movement of the blocks along the bending arc of the pipe.

13. A pipe bender comprising a table, clamping means on the table for securing one end of a pipe in position, a frame pivoted on the table, a bending block in the frame, means on the frame for forcing the block against the pipe to cause bending of said pipe, a movable forming block adapted to support the pipe inwardly of the bending block when the pipe is being bent, said frame being swingable on its pivot so that the pipe may be progressively bent along the desired arc, a second frame having a common pivot with the first frame and carrying the forming block, springs tending to retain the frames in a substantially vertical position, and means removably connecting the bending block with the forming block for simultaneous movement along the bending arc of the pipe.

14. A pipe bender comprising a table, clamping means on the table for securing one end of a pipe in position, a frame pivoted on the table, a bending block in the frame, means on the frame 55 for forcing the block against the pipe to cause bending of said pipe, a movable forming block adapted to support the pipe inwardly of the bending block when the pipe is being bent, said frame being swingable on its pivot so that the 60 pipe may be progressively bent along the desired arc, a second frame having a common pivot with the first frame and carrying the forming block, springs tending to retain the frames in a substantially vertical position, and means removably 65 connecting the bending block with the forming block for simultaneous movement along the bending arc of the pipe, a resilient means projecting from the table and through the second frame for supporting the upper end of the frame when the 70 forming block is being secured to said frame.

THOMAS W. DELANEY,
